Related U.S. Application Data

(62) Division of application No. 29/449,312, filed on Mar. 14, 2013, now Pat. No. Des. 746,552.

Primary Examiner — John Windmuller(51) LOC (10) Cl. ..... 02-02Assistant Examiner* — Luqman McNeil(52) U.S. Cl.(74) Attorney, Agent, or Firm — Morgan, Lewis & Bockius LLPUSPC ..... D2/731*CLAIM(58) Field of Classification Search

The ornamental design for a sports shirt, as shown and described.

USPC D2/731, 717, 840, 847, 700; 2/227, 69, 2/115; 602/19, 2; 450/8; 139/319
CPC A41D 13/0015; A41D 13/1245; A41D 1/002; A41D 13/0012; A41D 13/0058; A61F 5/026; A41C 1/10DESCRIPTION

See application file for complete search history.

FIG. 1 is a front view of a sports shirt, showing a first embodiment of a new design;

(56) References Cited

FIG. 2 is a front view of a sports shirt, showing a second embodiment of the design; and,

U.S. PATENT DOCUMENTS

FIG. 3 is a rear view of the sports shirt shown in FIG. 1 or FIG. 2.

The broken lines represent the portions of the sports shirt that form no part of the claimed design. The solid black shading indicates color contrast with the non-shaded portions of the sports shirts, and no particular color is claimed.
